MONOAZO DYESTUFFS

Richard Fleischhauer, Frankfort-on-the-Main-Fechenheim, Carl Theo Schultis, Bergen, near Frankfort-on-the-Main, and Ernst Korten, Frankfort-on-the-Main-Fechenheim, Germany, assignors to General Aniline & Film Corporation, a corporation of Delaware

No Drawing. Application June 1, 1939, Serial No. 276,806. In Germany June 2, 1938

4 Claims. (Cl. 260—199)

Our present invention relates to valuable monoazo dyestuffs, more particularly to those of the general formula

wherein R means a radicle of the benzene series, R₁ stands for a member of the group consisting of aliphatic, hydroaromatic and aromatic radicles, R₂ for a member of the group consisting of aliphatic and hydroaromatic radicles containing less than 10 carbon atoms, R₁ and R₂ together containing at least 14 carbon atoms, X stands for a member of the group consisting of carbonyl (CO) and sulfonyl (SO₂), Y for a member of the group consisting of alkyl and aryl groups of the benzene series, said aryl group being directly linked to X by a nuclear carbon atom of the benzene nucleus, one Z stands for the sulfonic acid group (SO₃H) and the other for hydrogen.

The new dyestuffs surpass the analogous dyestuffs as to fastness of the dyeings obtained therewith particularly to washing, fulling, sea-water, perspiration and to light and mostly by the valuable capability of being well fixed on animal fibers from a neutral bath.

Surprisingly in spite of the very high molecular weight they are mostly well watersoluble, in many cases even better, than the analogous dyestuffs of a lower molecular size.

The diazo components which are used for the manufacture of the present dyestuffs are, for instance, obtainable by acting with nitrobenzenecarboxylic acid halides, which may contain further substituents in the benzene nucleus, on amines of the formula

wherein R₁ and R₂ have the aforesaid significance and reducing the nitro compounds thus formed. Among the secondary amines of this type there may be named for instance: di-isoheptylamine, di-(α -ethyl-hexyl)-amine, di-n-heptylamine, di-n-octylamine, di-n-nonylamine, or mixtures of such amines, N-n-butyl-1-aminonaphthalene, N-cyclohexyl-1-aminonaph-

thalene, N-cyclohexyl-2-aminonaphthalene, N-dodekahydrodiphenyl-aniline, N-(isohexyl-cyclohexyl)-aniline, N-(isooctyl-cyclohexyl)-aniline, N-(isohexylphenyl)-cyclohexylamine, N-ethylidodecylamine, di-hexahydrobenzylamine, N-hexahydrobenzyl-dodecylamine and the like.

The normal aliphatic secondary amines, for instance the di-n-octylamine or the di-n-nonylamine are obtained in known manner, for instance, from the corresponding alcohols which are prepared from the corresponding fatty acids by treating them with ammonia in the presence of a dehydration catalyst. The secondary iso-alkylamines with a branched chain probably have the following constitution:

They are obtained, for instance, from the corresponding aldehydes, which are, for example, obtained as by-products in the methanol synthesis, by treating them under pressure with hydrogen and ammonia.

By causing the corresponding aliphatic or cycloaliphatic alcohols or halogen derivatives to react with amines the secondary amino compounds otherwise named may be obtained in known manner.

In order to further illustrate our invention the following examples are given, the parts being by weight. We wish it however to be understood that our invention is not limited to the particular products or reaction conditions mentioned therein.

Example 1

The diazo solution obtained from 36 parts of N-(3-amino-benzoyl)-N,N-[di-(α -ethylhexyl)]-amine of the formula

is added, while cooling, to an aqueous solution of 43 parts of 1-benzoylamino-8-hydroxynaphthalene-4,6-disulfonic acid containing an excess

of sodium carbonate. The dyestuff thus formed of the formula

is, when dry, a watersoluble dark red powder and dyes wool from an acid or neutral bath bright bluish red shades of a very good fastness to washing, fulling, perspiration, seawater and light.

When using as coupling component 1-(2',5'-dichlorobenzoyl)amino-8-hydroxynaphthalene-4,6-disulfonic acid or the corresponding 3,6-disulfonic acid compound, the formed dyestuffs dye bright scarlet and somewhat more bluish red shades respectively.

Example 2

The diazo solution of 34.4 parts of N-(3'-aminobenzoyl)-N-cyclohexyl-1-aminonaphthalene is added, while cooling, to an aqueous solution of 50 parts of 1-(2',5'-dichlorobenzoyl)amino-8-hydroxynaphthalene-4,6-disulfonic acid, containing an excess of sodium carbonate.

The dyestuff thus obtained of the formula

is, when dry, a watersoluble brownish red powder and dyes wool or silk bright red shades of a good fastness to washing, fulling, perspiration, seawater and light.

When starting from N-(3'-aminobenzoyl)-N-n-butyl-1-amino-naphthalene the formed dyestuff is a bluish red powder and dyes wool very similar shades.

Example 3

36 parts of a mixture of amino compounds obtained by reducing the condensation product of 4-nitrobenzoylchloride and a mixture of secondary amines of the constitution

are diazotized in the usual manner. The diazo solution thus obtained is added at about 5 to 10° C. to a solution of 53 parts of 1-(2',5'-dimethyl-4'-chlorobenzenesulfamino)-8-hydroxynaphthalene-3,6-disulfonic acid containing an excess of

sodium carbonate. The dyestuff thus obtained of the formula

is, when dry, a watersoluble red powder and dyes wool and silk bright bluish red shades of the same good fastness properties as the dyestuffs of the foregoing examples.

A similar dyestuff is obtained when using as coupling component the 1-(2',5'-dichlorobenzoyl)amino-8-hydroxynaphthalene-3,6-disulfonic acid.

When using the diazo compound of a mixture of amino compounds obtained by condensing instead of 4-nitrobenzoylchloride 3-nitro-4-methoxybenzoylchloride with the aforesaid mixtures of secondary amines and subsequent reduction, the formed dyestuff dyes substantially more bluish red shades.

The analogous dyestuff of the formula

is, when dry, a watersoluble red powder and dyes wool bright yellowish red shades of similar fastness properties.

The analogous dyestuff containing in the 4-position of the benzene nucleus a methyl group dyes wool somewhat more bluish red shades.

Example 4

The diazo compound of 38.6 parts of N-(3-aminobenzoyl)-N-dodekahydrodiphenyl-2'-methylphenylamine is combined in the presence of an excess of caustic chalk with 53 parts of 1-(2',5'-dimethyl-4'-chlorobenzenesulfamino)-8-hydroxynaphthalene-3,6-disulfonic acid.

The dyestuff thus formed of the formula

is, when dry, a red powder and dyes wool bright red shades of good fastness properties.

Similar dyestuffs are obtained by starting from diazo compounds of amines obtained by the reduction of condensation products of 3- and 4-nitrobenzoylchloride with N-(isohexylcyclohexyl)-phenylamine, N-(isooctyl-cyclohexyl)-phenylamine, N-(isohexylphenyl)-cyclohexylamine, N-ethyldecylamine, N-dodecyl-cyclohexylamine and similar secondary amines.

The following table will serve to furnish further examples of dyestuffs embraced by our invention, listing the components of the said dyestuffs in separate columns and indicating the shades of each when dyeing on wool.

2. The monoazo dyestuff of the formula

Diazo-component	Coupling component	Shade
N-(4-aminobenzoyl)-N, N-(di-isoheptyl)-amine	1-(2', 5'-dichlorbenzoylamino)-8-hydroxynaphthalene-4, 6-disulfonic acid.	Red.
N-(3-aminobenzoyl)-N, N-(di-isoheptyl)-amine	1-(3'-nitrobenzoylamino)-8-hydroxynaphthalene-4,6-disulfonic acid.	Bluish red.
N-(4-aminobenzoyl)-N, N-[di-(a-ethyl-hexyl)]-amine	1-benzoylamino-8-hydroxynaphthalene-3, 6-disulfonic acid.	Do.
N-(3-aminobenzoyl)-N, N-[di-(a-ethyl-hexyl)]-amine	1-(2',5'-dimethyl-4'-chlor -benzenesulfoamino) - 8 - hydroxynaphthalene-3,6-disulfonic acid.	Bright bluish red
N-(3'-aminobenzoyl)-N-(n-butyl)-1-amino-naphthalene	1-(2',5'-dimethyl-4'-chlorbenzenesulfoamino) - 8 - hydroxynaphthalene-3,6-disulfonic acid.	Do.
N-(3'-aminobenzoyl)-N-cyclohexyl-1-aminonaphthalene	1-(2',5'-dichlorbenzoylamino)-8-hydroxynaphthalene-4,6-disulfonic acid.	Red.
N-(3'-aminobenzoyl)-N-cyclohexyl-1-aminonaphthalene	1-(2',5'-dichlorbenzoylamino)-8-hydroxynaphthalene-3,6-disulfonic acid.	Bluish red.
N-(4'-aminobenzoyl)-N-cyclohexyl-1-aminonaphthalene	1-benzoylamino-8-hydroxynaphthalene-3,6-disulfonic acid.	Do.
N-(3'-aminobenzoyl)-N-cyclohexyl-2-aminonaphthalene	1-(2',5'-dichlorbenzoylamino)-8-hydroxynaphthalene-4,6-disulfonic acid.	Red.
N-(4'-aminobenzoyl)-N-isohexyl-1-amino-naphthalene	1-benzoylamino-8-hydroxynaphthalene-3,6-disulfonic acid.	Bluish red.
N-(3'-aminobenzoyl)-N-isooctyl-1-amino-naphthalene	do	Red.
N-(4'-aminobenzoyl)-N-isoctyl-1-amino-naphthalene	do	Bluish red.
N-(3-aminobenzoyl)-N-(dodekahydro-diphenyl)-phenylamine	1-benzoylamino-8-hydroxynaphthalene-3,6-disulfonic acid.	Bright red.
Do	1-acetylaminio-8-hydroxynaphthalene-3,6-disulfonic acid	Do.
Do	1-(4'-methylbenzenesulfoamino)-8-hydroxynaphthalene-3,6-disulfonic acid.	Bluish red.
N-(4'-aminobenzoyl)-N-(4-isoctylphenyl)-cyclohexylamine	1-(2',5'-dimethyl-4'-chlorbenzenesulfoamino) - 8 - hydroxynaphthalene-3,6-disulfonic acid.	Do.
Do	1-(2',5'-dichlorbenzoylamino)-8-hydroxynaphthalene-4,6-disulfonic acid.	Red.
N-(3'-aminobenzoyl)-N-(4-isoctylphenyl)-cyclohexylamine	1-acetylaminio-8-hydroxynaphthalene-3,6-disulfonic acid	Do.
Do	1-benzoylamino-8-hydroxynaphthalene-4,6-disulfonic acid	Do.
Do	1-(2',5'-dichlorbenzoylamino)-8-hydroxynaphthalene-3,6-disulfonic acid.	Bluish red.
N-(3'-aminobenzoyl)-N-(4-isohexylphenyl)-cyclohexylamine	1-(2',5'-dichlorbenzoylamino) - 8 - hydroxynaphthalene - 4,6-disulfonic acid.	Red.
N-(4'-aminobenzoyl)-N-(4-isohexylphenyl)-cyclohexylamine	1-(2',5'-dimethyl-4'-chlorbenzenesulfoamino) - 8 - hydroxynaphthalene-3,6-disulfonic acid.	Bluish red.
N-(3-aminobenzoyl)-N-dodecyl-cyclohexylamine	1-acetylaminio-8-hydroxynaphthalene-4,6-disulfonic acid	Yellowish red.
N-(4-aminobenzoyl)-N-dodecyl-cyclohexylamine	1-benzoylamino-8-hydroxynaphthalene-3,6-disulfonic acid	Bluish red.
N-(4-aminobenzoyl)-N-dodecyl-cyclohexylamine	1-(2',5'-dimethyl-4'-chlorbenzenesulfoamino) - 8 - hydroxynaphthalene-3,6-disulfonic acid.	Do.
N-(4-aminobenzoyl)-N-ethyl-dodecylamine	1-acetylaminio-8-hydroxynaphthalene-4,6-disulfonic acid	Do.
N-(4-aminobenzoyl)-N-dodecylphenylamine	1-(2',5'-dichlorbenzoylamino) - 8 - hydroxynaphthalene - 3,6-disulfonic acid.	Do.
N-(4'-aminobenzoyl)-N-(4-isohexylcyclohexyl)-phenylamine	1-benzesulfoamino-8-hydroxynaphthalene-3,6-disulfonic acid.	Do.

We claim:

1. Monoazo dyestuffs of the general formula

wherein R means a radicle of the benzene series, R₁ stands for a member of the group consisting of aliphatic, hydroaromatic and aromatic radicles, R₂ for a member of the group consisting of aliphatic and hydroaromatic radicles containing less than 10 carbon atoms, R₁ and R₂ together containing at least 14 carbon atoms, X stands for a member of the group consisting of carbonyl (CO) and sulfonyl (SO₂), Y for a member of the group consisting of alkyl and aryl groups of the benzene series, said aryl group being directly linked to X by a nuclear carbon atom of the benzene nucleus, one Z stands for the sulfonic acid group (SO₃H) and the other for hydrogen, which dyestuffs dye the animal fibers mostly reddish shades of a good fastness particularly to washing, fulling, seawater, perspiration and light.

which dyestuff is when dry a watersoluble brownish red powder and dyes animal fibers bright red shades of a good fastness particularly to washing, fulling, seawater, perspiration and light.

3. The monoazo dyestuff of the formula

which dyestuff is when dry a watersoluble red powder and dyes animal fibers bright bluish red shades of a good fastness particularly to washing, fulling, seawater, perspiration and light.

4. The monoazo dyestuff of the formula:

which dyestuff is, when dry, a watersoluble red powder and dyes animal fibers bright red shades of a good fastness, particularly to washing, fulling, seawater, perspiration and light.
